ART OF CRACKING HYDROCARBONS.

Application filed July 21, 1927. Serial No. 207,476.

This invention relates to improvements in the cracking of heavier and higher boiling hydrocarbon oils for the production of lighter and lower boiling hydrocarbon oils. 5 In particular, the invention relates to improvements in such operations where the heavier or higher boiling oil is cracked while in the vapor phase. 10 The invention is of special value and application in the production of gasolines or motor fuels having a relatively high critical compression or having anti-knock properties when burned in the usual type of internal combustion gasoline engine. 15 The products of operations in which relatively intense or relatively severe cracking conditions are maintained include, if the conditions are appropriate, constituents of special value as components of motor fuels. 20 With many more refractory stocks, such as kerosene and light gas oil, the more advantageous range of cracking temperatures lies above the critical temperature of the stock so that the operation must be carried out substantially in the vapor phase if such relatively intense or relatively severe cracking conditions are maintained. With heavier or higher boiling and less refractory stocks, such as heavy gas oil, the more advantageous 25 range of cracking temperatures may not exceed the critical temperature of the stock, but even in such cases the pressures necessary to maintain any substantial part of the stock in liquid phase are usually extremely high.

This invention relates particularly to operations in which the heavier and higher boiling oil is heated in the vapor phase to a high cracking temperature, that is to a cracking temperature upwards of 900° F. Small amounts of tarry matter or carbonaceous matter formed during the cracking operation or very small amounts of very heavy constituents of the stock may be carried in the oil-vapor mixture as a fog or mist, but the predominating proportion of the oil is in the vapor phase throughout the cracking operation.

Such relatively intense or relatively severe cracking conditions result in the formation of a large proportion of unsaturated hydrocarbons. Some of these unsaturated hydrocarbons are objectionable as components of motor fuel, and are removed by suitable treatment before the cracked product is

ready for use as motor fuel, but many of these unsaturated hydrocarbons are the very constituents which serve to give the cracked product its special value as motor fuel, that is which give the gasoline or motor fuel so produced a relatively high critical compression or anti-knock properties. Many of these desirable unsaturated constituents are unstable at elevated temperature, even at temperatures not much above the ordinarily encountered atmospheric temperatures.

From the stand point of heat economy and of elimination of otherwise necessary operations and the apparatus required to carry out such operations, it is desirable to fractionate directly the products of such cracking operations to secure a gasoline or motor fuel fraction which does not require further distillation or redistillation. In the production of gasolines or motor fuels intended to contain such desirable unsaturated constituents in large amounts such further distillation or redistillation is doubly undesirable because it again subjects such constituents to elevated temperatures.

It has previously been suggested to reintroduce into direct contact with the vapors in the fractionating operation to which the vapor mixture from a cracking operation is subjected a portion of the final gasoline or motor fuel product for effecting or promoting accurate separation of the gasoline or motor fuel product. This scheme of operation is of value so far as effecting or promoting direct fractionation is concerned, but when it is applied to the fractionation of the vapor mixture from vapor phase cracking operations in which the oil vapors are subjected to high cracking temperatures it frequently results in severe and excessive losses, apparently due to the instability of unsaturated constituents of the cracked product. When reintroduced into such fractionating operations, such unsaturated constituents are of necessity subjected to the elevated temperatures prevailing in the fractionating operation, and part of them may even be subjected to higher temperatures where the heavier components condensed in the fractionating operation are again heated, as for example by return to the cracking operation proper.

This invention provides an improved method of operation which, although providing for direct fractionation, eliminates

such losses, and which has several further important advantages.

According to the present invention, the heavier or higher boiling hydrocarbon oil to be cracked is heated in the vapor phase to a high cracking temperature and, before condensation of the desired lighter and lower boiling oil, the vapors from the vapor phase cracking operation are subjected to a fractionating operation where an oil of which at least a substantial portion is vaporized in the fractionating operation but which is substantially free from unsaturated components produced in the vapor phase cracking operation or unstable at the temperatures prevailing in the fractionating operation or at higher temperatures is introduced into direct contact with the vapors as a cooling and condensing agent. Advantageously, this oil introduced into the fractionating operation as a cooling and condensing agent is of boiling range corresponding to that of the desired product, for example, in the production of gasoline it is advantageous to use a gasoline fraction as a cooling and condensing agent in the fractionating operation. The oil for cooling and condensing the vapors in the fractionating operation, however, may contain some higher boiling components, advantageously not more than about 20% of components boiling off at a temperature above the end boiling point of the desired product, at atmospheric pressure. Or, an oil containing some components corresponding in boiling range to the desired product but also containing a substantial proportion of heavier components may be introduced into the vapors in the fractionating operation as a cooling and condensing agent at the same time being fractionated therein.

Lighter and lower boiling components of the oil introduced into the fractionating operation in accordance with this invention which are suitable as components of the desired product may thus be blended with the vapors of the desired product produced in the cracking operation. For example, straight run gasoline or gasoline from other cracking operations free from such unstable unsaturated constituents required to be blended with the gasoline produced in the vapor phase cracking operation may be utilized as a cooling and condensing agent in the fractionating operation and at the same time blended with the gasoline produced in the vapor phase cracking operation. The vapors from the fractionating operation, including vapors produced in the vapor phase cracking operation and vaporized components of the oil introduced into the vapors in the fractionating operation as a cooling and condensing agent, are advantageously subjected to treatment with an absorbent earth or clay, in accordance with

the present invention, before condensation to form the desired lighter and lower boiling oil. In this way, the cracked vapors are subjected to treatment while fresh from the cracking operation and part of the heat carried away from the cracking operation by the vapors may be utilized for effecting or promoting the refining treatment, any components blended with the vapors in the fractionating operation being at the same time subjected to the same treatment. The cracked product, or the composite product, may thus be stabilized, chemically and physically, as part of the complete operation by direct fractionation and direct treatment. A marketable gasoline or motor fuel, for example, may thus be produced directly without requiring further treatment or distillation or blending. Gasoline or gasoline-containing oil introduced into the fractionating operation as a cooling and condensing agent, however, may be subjected to treatment before being so introduced into the fractionating operation.

The invention will be further described in connection with the accompanying drawing which illustrate, in a diagrammatic and conventional manner, in elevation and partly in section, one form of apparatus adapted for carrying out one type of operation in which the improvement of the present invention is embodied, but it is intended and will be understood that this further description and illustration are for the purpose of exemplification and that the invention is not limited thereto.

Referring to the drawing, the apparatus illustrated comprises a heating conduit 1 arranged in the heating flue of a furnace 2, a series of digesting drums 4 arranged in a corresponding series of flues in the heating chamber 36, a scrubbing tower 6, a reflux tower 8, a fractionating tower 10, a treating tower 20, a condenser 25, a separator and receiver 30, coolers 18, 19 and 15, pumps 16, 17 and 12, and appropriate connections. The scrubbing tower 6, for the separation of entrained tarry or carbonaceous constituents, may be provided interiorly with baffles, best in its upper part. The reflux tower 8 may be of any construction suitable for refluxing the vapors; for example, it may be an ordinary baffle tower. The fractionating tower 10 may be of any construction suitable for accurate fractionation of the vapors; for example, it may be an ordinary bubble tower. The treating tower 20 may be of any suitable construction adapted to hold a body of the refining agent, such as fuller's earth or a treated clay, and to provide for passage of the vapors therethrough. These towers, particularly towers 6, 8 and 10, may with advantage be thoroughly lagged or thermally insulated to prevent or reduce heat loss. The condenser 25 and the coolers 18, 19 and 130

15 may be of ordinary construction. The separator and receiver 30 is advantageously provided with baffles above the point of discharge of the connection from the condenser 25 to promote a clean separation between condensate and gases and vapors remaining uncondensed. The pump 17 should be adapted to handle oil at relatively high temperature.

10 In carrying out the invention in the apparatus illustrated, for the production of gasoline or motor fuel for example, oil is supplied to the heating conduit 1 and there vaporized and heated to a high cracking temperature and the resulting vapors are then passed, by means of connection 3, to the digesting drums 4 through which they pass serially. The temperature of the vapors as they are discharged from the heating conduit 1 may approximate 1,000° F.-1,200° F. and the temperature of the vapors as they are discharged from the last digesting drum may approximate 950° F.-1,200° F. Heat for maintaining the required temperature in the digesting drums 4 may be supplied to the flues in the heating chamber 36 in any suitable manner. From the last digesting drum, the oil vapor, with any entrained tarry or carbonaceous matter, passes to the scrubbing tower 6 through connection 5. Vapors from this tower pass to the reflux tower 8 through connection 7 and vapors remaining uncondensed in the reflux tower 8 pass to the fractionating tower 10 through connection 9. Vapors remaining uncondensed in the fractionating tower escape through connection 13 either to the condenser 25 through connection 32 or to the treating tower 20 through connection 29 and thence to the condenser 25 through connection 33. The condenser 25 discharges into the separator and receiver 30 through connection 34. Uncondensed vapors and gases are discharged from this separator and receiver through connection 35 and the condensate through connection 31. Raw stock is supplied to the upper end of reflux tower 8 by means of pump 16 through connection 28, or part of the raw stock may be supplied directly to the heating conduit 1 through connections 27 and 26. A part of the oil mixture discharged from the lower end of reflux tower 8 through connection 21 is introduced into the upper end of the scrubbing tower 6 through connections 22 and 23 by means of pump 17 to effect the separation of tarry and carbonaceous matter therein, the oil so introduced being largely vaporized again to escape through connection 7. The remaining oil mixture discharged through connection 21, or part of it, is returned to the heating conduit 1 through connections 22, 24 and 26 by means of pump 17. The tarry and carbonaceous matter separated in the scrubbing tower usually remains fluid while hot and may be discharged through connection 38 and the cooler 18. Oil mixture discharged through connection 21 in excess of that introduced into the scrubbing tower and supplied to the heating conduit may be discharged through cooler 19. The condensate separated from the vapor mixture in the fractionating tower 10 is discharged through connection 14 and cooler 15. The cooling and condensing agent for effecting or controlling the fractionating operation carried out in the fractionating tower 10 is supplied to the upper part of this tower through connection 11 by means of pump 12. The temperature of the vapors escaping from the scrubbing tower 6 may be maintained in the neighborhood of 500° F.-550° F., the temperature of the vapors escaping from the reflux tower 8 in the neighborhood of 350° F.-450° F., and the temperature of the vapors escaping from the fractionating tower 10 in the neighborhood of 300° F.-380° F. In the cracking operation, it is advantageous to use only sufficient pressure to force the oil or oil vapor through the apparatus; the pressure in the digesting drums, for example, may be but a fraction of a pound or but a few pounds per square inch above atmospheric pressure, although considerably higher pressures may be required at the inlet of the heating conduit to maintain the desired rate of flow therethrough.

Where the vapors escaping from the fractionating tower 10 are to be subjected to treatment with an absorbent earth or clay before condensation to form the desired product, they are passed through the treating tower 20 in which they are contacted, for example, with a body of fuller's earth or treated clay. Any oil condensing or collecting in this tower is discharged through connection 37. The vapors escaping from the fractionating tower, however, may be discharged directly to the condenser 25.

In carrying out the present invention in the apparatus illustrated, for the production of gasoline or motor fuel, a gasoline from some external source, or a gasoline fraction, or a naphtha fraction containing a substantial portion of gasoline, is introduced into the upper end of the fractionating tower 10 through connection 11 as required to effect the necessary condensation therein. The rate of supply of such gasoline or gasoline-containing oil, for example, may be regulated to maintain the temperature of the escaping vapors at an appropriate predetermined value. This gasoline or gasoline-containing oil, for example, may be a straight run gasoline, or a gasoline from some other cracking operation, such as a gasoline produced by pressure distillation in which the stock supplied to the cracking operation is subjected to relatively mild cracking conditions, or a mixture of such

gasolines. The gasoline so introduced, or that portion of it suitable as a component of the desired product, is vaporized by heat exchange in the fractionating operation and the resulting vapors escape through connection 13 together with the vapors from the vapor phase cracking operation. Any heavier components of the gasoline or gasoline-containing oil so introduced into the fractionating tower 10 are, in the same fractionating operation, separated from the vapors subsequently condensed to form the desired gasoline or motor fuel product. Similarly, naphtha fractions from the straight running 10 of crude petroleum or fractions of crude petroleum, or pressure distillates including gasoline produced by relatively mild cracking together with heavier components, may be supplied to the upper end of the fractionating tower 10 through connection 11 as a cooling and condensing agent. The lighter components of such naphtha fractions or pressure distillates, suitable as components of the desired product, are then separated from the heavier components escaping with the vapors of the desired product produced in the vapor phase cracking operation.

The vapors of the desired lighter and lower boiling product, gasoline or motor fuel for example, may be condensed without further treatment. These vapors, including the vapors produced in the vapor phase cracking operation and vaporized components of the oil introduced into the vapors in the fractionating operation as a cooling and condensing agent, are however advantageously subjected to refining treatment with an absorbent earth or clay after they leave the fractionating operation and before they are condensed to form the desired product. In this manner, the invention makes it possible to produce a finished gasoline or motor fuel in a single operation, the operation including any necessary or desired blending as well as treatment of the composite product combined in the operation in a particularly advantageous way.

I claim:

1. In cracking hydrocarbon oils for the production of lighter and lower boiling oils, the improvement which comprises heating the oil in the vapor phase to a high cracking temperature and, before condensation of the desired lighter and lower boiling oil, subjecting the vapors from the cracking operation to a fractionating operation, and introducing into direct contact with the vapors in the fractionating operation, as a cooling and condensing agent, an oil of boiling range corresponding to that of the desired lighter and lower boiling oil but substantially free from unsaturated components unstable at the temperatures prevailing in the fractionating operation.

2. In cracking hydrocarbon oils for the

production of lighter and lower boiling oils, the improvement which comprises heating the oil in the vapor phase to a high cracking temperature and, before condensation of the desired lighter and lower boiling oil, subjecting the vapors from the cracking operation to a fractionating operation, and introducing into direct contact with the vapors in the fractionating operation, as a cooling and condensing agent, an oil of boiling range 75 corresponding to that of the desired lighter and lower boiling oil but substantially free from unsaturated components produced in the vapor phase cracking operation.

3. In cracking hydrocarbon oils for the production of lighter and lower boiling oils, the improvement which comprises heating the oil in the vapor phase to a cracking temperature upwards of 900° F. and, before condensation of the desired lighter and lower boiling oil, subjecting the vapors from the cracking operation to a fractionating operation, and introducing into direct contact with the vapors in the fractionating operation, as a cooling and condensing agent, 90 an oil not more than 20% of which boils off at a temperature above the end boiling point of the desired lighter and lower boiling oil, at atmospheric pressure, and which is substantially free from unsaturated components 95 unstable at the temperatures prevailing in the fractionating operation.

4. In cracking hydrocarbon oils for the production of lighter and lower boiling oils, the improvement which comprises heating the oil in the vapor phase to a cracking temperature upwards of 900° F. and, before condensation of the desired lighter and lower boiling oil, subjecting the vapors from the cracking operation to a fractionating operation, and introducing into direct contact with the vapors in the fractionating operation, as a cooling and condensing agent, an oil not more than 20% of which boils off at a temperature above the end boiling point 100 of the desired lighter and lower boiling oil, at atmospheric pressure, and which is substantially free from unsaturated components 105 unstable at the temperatures prevailing in the fractionating operation.

5. In cracking hydrocarbon oils for the production of lighter and lower boiling oils, the improvement which comprises heating the oil in the vapor phase to a high cracking temperature and, before condensation of the desired lighter and lower boiling oil, subjecting the vapors from the cracking operation to a fractionating operation, introducing into direct contact with the vapors in the fractionating operation, as a cooling and condensing agent, an oil of which at least 110 a substantial portion is vaporized therein and escapes with the vapors from the fractionating operation but which is substantially 115 free from unsaturated components produced in the vapor phase cracking operation.

130

duced in the vapor phase cracking operation, and separately condensing the vapors from the fractionating operation to form the desired lighter and lower boiling oil.

- 5 6. In cracking higher boiling hydro-
carbon oils for the production of gasoline, the improvement which comprises heating the higher boiling oil in the vapor phase to a cracking temperature upwards of 900° F. 40
10 and, before condensing the gasoline so produced, subjecting the vapors from the cracking operation including such gasoline to a fractionating operation to condense compo-
nents higher boiling than the gasoline, in-
15 troducing into direct contact with the vapors in the fractionating operation, as a cooling and condensing agent, a gasoline fraction substantially free from unsaturated com-
20 ponents produced in the vapor phase crack-
ing operation, and separately condensing the gasoline vapors, including vapors of the gasoline produced in the cracking operation and vaporized components of the gasoline fraction introduced into the vapors in the
25 fractionating operation, escaping from the fractionating operation. 45
7. In cracking hydrocarbon oils for the production of lighter and lower boiling oils, the improvement which comprises heating
30 the oil in the vapor phase to a high cracking temperature and, before condensation of the desired lighter and lower boiling oil, subjecting the vapors from the cracking opera-
35 tion to a fractionating operation, intro-
ducing into direct contact with the vapors in the fractionating operation, as a cooling and condensing agent, an oil of which at least a substantial portion is vaporized therein and escapes with the vapors there- 50
from but which is substantially free from unsaturated components produced in the vapor phase cracking operation, subjecting the vapors from the fractionating operation, including vapors produced in the cracking operation and vaporized components of the oil introduced into the vapors in the fractionating operation, to treatment with an absorbent earth, and thereafter condensing the remaining vapors to form the desired lighter and lower boiling oil. 55
8. In cracking higher boiling hydrocarbon oils for the production of gasoline, the improvement which comprises heating the higher boiling oil in the vapor phase to a cracking temperature upwards of 900° F. 55
and, before condensing the gasoline so introduced, subjecting the vapors from the cracking operation including such gasoline to a fractionating operation to condense components higher boiling than the gaso-
60 line, introducing into direct contact with the vapors in the fractionating operation, as a cooling and condensing agent, a gasoline fraction substantially free from unsaturated components produced in the vapor phase 65
cracking operation, subjecting the vapors, including vapors of the gasoline produced in the cracking operation and vaporized components of the gasoline fraction introduced into the vapors in the fractionating operation, escaping from the fractionating operation to treatment with an absorbent earth and thereafter condensing the remain-
ing gasoline vapors. 70
In testimony whereof, I have subscribed
my name.

EDWARD W. ISOM.
